UNITED STATES PATENT OFFICE.

JAMES WEBB ROGERS, OF NEW YORK, N. Y.

ELECTRIC CONDUCTOR OR CABLE.

SPECIFICATION forming part of Letters Patent No. 280,518, dated July 3, 1883.

Application filed April 26, 1883. (No model.)

To all whom it may concern:

Be it known that I, JAMES WEBB ROGERS, a citizen of the United States, and resident of New York, in the county of New York and State of New York, have invented certain new and useful Improvements in Electric Conductors or Cables, of which the following is a specification.

My invention relates to the construction and methods of using electric cables designed for use in connection with telegraphs, telephones, electric lights, transmission of power, or other purposes; and its object is primarily to improve the conductivity and the ease of construction.

In carrying out my invention I propose to use thin ribbons or strips of some conducting material—such as copper—separated by tapes or strips of asbestos cloth, the whole being secured together by sewing, or by bands of any suitable construction, or by any other desired means. In manufacturing copper strips or wires the process of drawing or rolling impairs the conductivity, and to restore to the metal its proper or highest conductivity it is necessary to anneal the same; but in the process of annealing thin copper ribbon is apt to become twisted and distorted, so that it cannot be built up into a cable so readily as when it first comes from the rolls. My invention overcomes this difficulty, since it supplies a means whereby the completed cable may be placed in the annealing-furnace without detriment to its structure, and the ribbon of copper or other material may be annealed after instead of before the cable is made.

My invention further consists in a novel method of manufacturing electric cables; and it consists in first applying to the conducting strips or wires insulating coverings or separating layers of asbestos, and in subsequently placing the completed cable in an annealing-furnace, whereby the conductivity of the copper may be improved.

In the accompanying drawings, Figure 1 is a cross-section of a cable constructed according to my invention, taken on the line 1 1 of Fig. 2. Fig. 2 is a longitudinal section of a portion of the cable taken on the line 2 2 of Fig. 1. Fig. 3 is a side view of a modified form of the cable. Fig. 4 shows a bundle of the completed

cable in an annealing-furnace. Fig. 5 illustrates a manner of using the cable, whereby extra or return currents may be neutralized. Fig. 6 illustrates diagrammatically the manner in which one neutralizing-conductor may be used in connection with several transmitting-conductors. Fig. 7 shows a detail of the transmitting-key shown in Fig. 6. Fig. 8 shows a method of using an extra neutralizing-conductor with the form of cable in which the metallic conductors form the elements of a battery. Fig. 9 shows how one battery may be made to take the place of the two batteries in Fig. 5.

Referring to Fig. 1, A A A, &c., indicate strips or ribbons of some conducting material, preferably copper, between which are placed ribbons or strips of asbestos cloth, preferably slightly wider than the copper strips, the whole being secured together by sewing or stitching with an asbestos thread or cord C. Strips or ribbons of asbestos are placed on the exterior, as indicated, to complete the insulation of the upper and lower copper strips, as shown.

In manufacturing my cable the copper ribbons are taken direct from the rolling-mill, since in this form they can be more readily manipulated and the cable more easily built, and after the cable has been built it is placed in suitable lengths in an annealing-furnace, D, Fig. 4, of any suitable kind, where the copper of the cable is subjected to the ordinary annealing process, whereby its conductivity is improved. In this process the cable suffers no injury, its insulating material being insensible to the action of the heat employed. After the annealing process is completed the cable is boiled in some repellent of water, such as oil, kerosene, or beeswax; or several repellents are mixed and the cable boiled in the mixture. It is then ready for use. The cable, as thus constructed, may be laid in trenches or boxes, or in other places where it will not be subjected to great tensile strain, and is ordinarily of sufficient strength for such purposes. It is, however, desirable to increase its tensile strength so far as possible, for which purpose I propose to substitute for one of the copper or other conductors a ribbon, A², of steel, iron, or other suitable material of greater tensile strength.

- The cable, as thus constructed, may have an outer protecting covering of any desired kind that would adapt it for use beneath the ocean or for crossing rivers.
- 5 Instead of the stitching or sewing of the strips together by an asbestos thread, the alternate conducting and non-conducting ribbons may, after being laid up, be bound together by wires, cords, or other suitable bindings, as indicated 10 at C² C², Fig. 3. If, however, the cable is to be subjected to the annealing process after it has been constructed, the binding C² must be of metal, asbestos, or other suitable material that will not be damaged by the heat.
- 15 If my cable be used for submarine telegraphs, or if it contain a multiplicity of conductors, each employed for the transmission of a separate message, it is quite necessary that the damaging and undesirable effects of what is 20 known as the "return-current" which follows the removal of the transmitting-battery should be avoided. To effect this result I make use of one of the conducting strips A, or of the strengthening wire or tape A², in connection 25 with a suitable battery and transmitting apparatus, whereby, upon the breaking or removal of the battery which serves to transmit signals through a conductor A, the same or another battery may be simultaneously connected 30 with its opposite pole to the extra conductor A². It is well known that when an electric current or pulsation passes in one of two parallel conductors it induces at the moment of passage a current in the opposite direction in the other conductor. It is this induced current which, acting in the main or transmitting conductor in an opposite direction to the return-current, serves in my invention to neutralize such return-current. One 35 of the forms of transmitting apparatus that may be employed for this purpose is shown in Fig. 5, where I have indicated a section of my improved cable containing a single transmitting-conductor A and a single neutralizing- 40 conductor A², said conductor A being connected to earth through a galvanometer, G, or other suitable receiving-instrument. At the transmitting end of the line are placed two batteries, M M², and a 45 transmitting-key, K, of ordinary construction, whose pivots are connected to the conductor A, while its front contact-stop is connected by wire 3 with the positive pole of both batteries M M². The back contact-stop or anvil of the 50 key is connected to earth. The negative pole of battery M is connected to earth, while the negative pole of battery M² is connected to the neutralizing-conductor A², as shown, and also to a contact-stop, a, with which an insulated 55 spring, c, mounted upon the key-lever, makes contact when the key is depressed. Said spring is connected by wire 5 with the earth, and when the key is at rest makes contact with an insulated contact-stop, b, connected by wire 6 with 60 the positive pole of battery M². When the key K is depressed for the purpose of sending the signal over conductor A, the currents from both

batteries M M² pass to line through the front contact-stop of the lever. The negative pole of M² is at this time connected to earth through the contact a and spring c. When the key is returned to its normal position and makes contact with its back stop, a return-current will flow from the line in the direction of the arrow h, both batteries being simultaneously disconnected from said line. At the same time, however, the contact-spring c makes contact with stop b, thus connecting the positive pole of M² to earth, while the negative pole of said battery is connected to wire A² through conductor 7, so as to cause an impulse on said line in the direction of arrow k, the effect of which is to induce in conductor A a current in the direction of arrow l, or counter to the return-current, thus neutralizing the latter. 85

Fig. 6 shows two transmitting-conductors and one neutralizing-conductor A² placed between them. At the transmitting end of the line, M M indicate two main batteries, each controlled by a transmitting-key, K, in the ordinary way, while M² indicates the neutralizing-battery, which serves to neutralize the return-current on either conductor. In this case battery M² does not assist in the transmission of the signal; but a suitable circuit-closing device is used with each key K, whereby, when said key is returned to its normal position, a current from the main battery M² is thrown upon line A² momentarily, but with an opposite polarity from that of batteries M on conductors A. The circuit-closing device for this purpose is so constructed as to close the connection only upon the return movement of the key, but not upon its movement in putting the battery to line. The construction of this device is shown more clearly in Fig. 7. 95

The contact-spring c is provided at its lower end with a hook the end of which, n, when the key is at rest, occupies the position shown in Fig. 7, so that when the spring rises, owing to the operation of the key, the hook passes up on the back side of an inclined insulating-block, m, bearing on its other side a conducting-plate, p, connected by wire 10 with the negative pole of battery M². Spring c is connected with the neutralizing-conductor A². When the key is fully raised the hook assumes the position shown in dotted line, Fig. 7, so that when the key returns to its normal position the hook passes down on the front of the inclined piece and makes momentary contact with the plate p at the instant the return-current flows from A, thus simultaneously causing a current from battery M² to flow in line A² in proper direction to neutralize by induction the return-current from A. 115

Fig. 8 illustrates the application of my invention to a submarine cable whose conductors are exposed to the action of the water, and are respectively electro-positive and electro-negative to one another. At each end of the line is shown a partial section of the cable composed of conducting-strips B² B³, one of which may be of copper and the other of zinc, sepa- 120 125 130

rated from one another by strips of asbestos B B, between which latter is included a strengthening-conductor, A², suitably protected from the water. B² B³ are connected, respectively, 5 with the two poles of galvanometer G, or other suitable receiving-instrument, at the distant end of the line, and at the transmitting end with the key K, so that when the latter is closed the currents of the battery formed by 10 the conductors B² B³ are short-circuited from the receiving-instrument G, thus causing a signal on the same.

In order to obviate the damaging effects of the polarization of the immersed conductors 15 B² B³, I make the transmitting-key K close the circuit of a battery, M³, through the interior conductor, A², which current is of proper polarity to induce in the exterior conductors a current that will dissipate or neutralize the 20 polarization of the battery formed by said conductors. This may be accomplished by causing the key K to close momentarily the circuit of M³ on the backstroke of the key through a conducting-spring, c, which is connected to 25 earth, as shown, and operates in conjunction with a block, M, constructed in the manner already described in connection with Fig. 7. Instead of using an extra neutralizing-battery, I may, by a suitable commutator or pole-changer, 30 make use of the transmitting-battery for neutralizing purposes. Such an arrangement is shown in Fig. 9, where K indicates the transmitting-key, whose back contact is connected with neutralizing-conductor A². The key K 35 operates with pole-changing springs of well-known construction (indicated at S) to place the battery M to line A with one polarity when the key is depressed, and to neutralizing-conductor A² with an opposite polarity when the 40 key returns to its normal position. When the key is depressed, the circuit is from earth through contact-stop 14, spring 13, battery M, spring 12, key-lever K, and to conductor A. The current of the battery is then removed 45 from conductor A². When the key returns to its normal position, the current is from earth through contact-stop 14, spring 12, battery M, spring 13, key-lever K, and line A², so that the battery is placed to line A² with an opposite 50 polarity from that which it had when placed to line A, and the return-current from A is neutralized in the manner already explained. Other circuit-closing devices may be used in place of those shown for closing the 55 circuit of a battery of other generator of electricity to the neutralizing-conductor at the proper time. I do not in any wise limit myself in this respect.

Other conducting materials may be used for 60 the strips or ribbons A, and the neutralizing-conductor A² might be of copper, as well as of a material that has greater tensile strength than copper. I am aware that cables made of strips of a suitable conductor and of strengthening strips or ribbons of iron or steel are not 65

new, and I therefore make no broad claim to such a cable. I have herein described the strengthening-ribbons as separated from the conductors A; but it would be within my invention to attach such strengthening-ribbon 70 directly to a conductor by soldering or otherwise.

I am aware that asbestos has been braided or otherwise applied to form a sheath for telegraph-wires; but in no instance of which I 75 am aware have strips or ribbons of copper been laid up with alternating asbestos ribbons to form a complete cable having many conductors. In my method of making a cable the asbestos may be used in the form of ribbons 80 woven on separate machines, and the work of making the cable consists only in laying up the ribbons or sheets of asbestos and copper as they come from separate machines, the number being multiplied according to the requirements. A cable as thus constructed can be made very cheaply and is exceedingly durable. 85

What I claim as my invention is—

1. A telegraph-cable composed of alternate strips or ribbons of copper or other good conducting material and asbestos, substantially as and for the purpose described. 90

2. An insulated electric conductor consisting of a cable composed of one or more strips or ribbons of copper or other good conducting material, one or more strips or ribbons of a material having greater tensile strength, and interposed insulating ribbons or strips of asbestos, substantially as and for the purpose described. 95

3. An electric cable composed of alternate strips or ribbons of copper and asbestos, the strips of said latter material being wider than those of copper. 100

4. The herein-described improvement in manufacturing cables composed of conducting strips or ribbons and interposed insulating-ribbons, which consists in taking the conducting-strip as it comes from the rolls, building the cable complete with asbestos as an insulating medium, and subsequently placing the completed cable in an annealing-furnace for the purpose of improving the conductivity of the conducting-strips. 105

5. The herein-described improvement in the method of manufacturing compound cables containing one or more conducting strips or ribbons, consisting in building up the cable with strips of asbestos as the insulating medium, and in subsequently placing the completed cable in an annealing-furnace and afterward applying to said cable any suitable repellent of moisture. 115

Signed at New York, in the county of New York and State of New York, this 23d day of April, A. D. 1883. 120

JAMES WEBB ROGERS.
